DERRICK PLATFORM STRUCTURE

William R. Sims, Carthage, Tex.

Application July 28, 1947, Serial No. 764,084

5 Claims. (Cl. 304—14)

1

This invention relates to new and useful improvements in derrick platform structures and more particularly to adjustable platforms adapted for use in oil well derricks.

One object of the invention is to provide an improved derrick platform structure which is so arranged as to be particularly adaptable for use in running or stabbing well casing, pipe or pump rods.

Another object of the invention is to provide an improved derrick platform which is adjustable vertically of a derrick as well as transversely thereof, whereby the platform may be positioned at different elevations and transverse projections to facilitate the coupling of well pipes of various lengths and, when not in use, may be retracted adjacent one of the sides of the derrick.

A further object of the invention is to provide an improved platform, of the character described, which is pivotally supported adjacent one of the sides of the derrick so as to be capable of being readily and compactly folded against the derrick side whenever desired.

Still another object of the invention is to provide an improved platform structure having a novel support whereby the platform structure may be readily and removably mounted in any derrick of conventional construction and whereby the same platform structure may be used in conjunction with a plurality of derricks.

Still another object of the invention is to provide an improved platform, of the character described, wherein means for controlling the vertical and transverse adjustments are operable from the supporting surface of the platform whereby a workman may make desired adjustments without leaving said platform.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a perspective view of a platform structure, constructed in accordance with the invention, and shown in its folded position mounted in a derrick.

Fig. 2 is a perspective view of the platform structure unfolded.

Fig. 3 is a plan view of the platform, showing a portion of its support.

Fig. 4 is a transverse, vertical, sectional view of the platform, its carriage and a portion of its support, and

2

Fig. 5 is a perspective view of the carriage.

In the drawings, the numeral 10 designates the usual inclined legs of a derrick having horizontal girders 11 and diagonal braces 12. A derrick platform structure 13 is adapted to be mounted in the derrick by means of a suitable support or frame 14, which is of substantially triangular shape and includes a pair of laterally-spaced, substantially upright guide rails or channels 15. A pair of inclined legs 16, having their upper ends converging toward and connected to the upper ends of the channels 15, are disposed opposite and in substantially the same vertical planes as said channels. Suitable cross braces or bars 17 connect and space the legs from the channels and each other. The upper and lower end of the channels are connected by similar bars or members 17'. For securing the frame 14 at desired elevations in the derrick, a plurality of flat bracket plates 18 are welded or otherwise secured to the legs 16 adjacent the cross braces 17 and are adapted to receive suitable J-bolts 18' which engage the girders 11. Thus, the legs are securely fastened to one side of the derrick in contiguous, parallel relation. The inclination of the legs is such that the channels 15 are substantially upright when said legs are fastened to one side of the derrick. It is pointed out that the frame 14 may be disposed at any desired elevation in a derrick and is provided with an eye bracket 19 at its top cross bar 17' to facilitate hoisting and positioning of the same.

A working platform, indicated generally by the numeral 20, is slidably mounted between the channels 15 by means of a carriage 21. As is most clearly shown in Fig. 5, the carriage 21 is of substantially triangular shape and is formed of suitable angle bars which are welded or otherwise secured together and includes a horizontal top portion 22 and an upright side portion 23 connected by inclined legs 24. Pairs of guide rollers or elements 25 are rotatably mounted upon horizontal shafts 26 which are preferably welded to the upright side portion 23 of the carriage at the upper and lower ends thereof. These rollers 25 engage within the channels 15 so as to slidably support said carriage therebetween.

For maintaining the carriage 21 in vertically-adjusted positions, suitable stops or detents 27 are secured on the external surfaces of the channels 15 at spaced intervals. A latch mechanism 28 is carried by the carriage 21 for coacting with the stops 27 and includes a rod or shaft 29 which extends transversely of the carriage upright portion 23 and has its end portions journaled in suitable brackets 30 mounted on said upright por-

tion. The ends of the shaft 29 project beyond the brackets 30 and have suitable latch elements or pawls 31 mounted thereon. As is most clearly shown in Figs. 1 and 2, the pawls 31 engage the stops 27 for maintaining the carriage in vertically-adjusted positions relative to the channels 15. For actuating the latching mechanism, a foot lever 32 is pivotally supported above the carriage by a suitable brace or bracket 33. A foot pedal 34 is provided upon the upwardly projecting end of the lever 32 and suitable pivoted links 35 and 36 connect the opposite end of said lever to the shaft 29. Since the link 36 is rigidly connected to the shaft, depression of the foot pedal and pivotal swinging of the lever 32 results in counter-clockwise rotation of said shaft so as to swing the pawls 31 outwardly out of engagement with the stops 27. A coiled or helical spring 37 is confined between the bracket 33 and the upwardly projecting end of the lever 32 for maintaining said lever in such position with the pawls in engagement with the stops. Although it is necessary to retract or swing the pawls away from the stops when it is desired to lower the carriage, due to the spring-pressed arrangement of the lever, said pawls will ride over said stops when said carriage is moved upwardly.

The platform 20 includes a supporting surface in the form of a deck or stage 38 which is supported by the carriage 21 and projects outwardly therefrom into the interior of the derrick. For pivotally mounting the stage 38, a pair of apertured ears or eyes 39 are secured to the top 22 of the carriage at opposite sides thereof adjacent its junction with the upright portion 23 and are adapted to receive a shaft or rod 40 carried by and extending transversely of said stage. The latter includes a pair of adjustable or telescoping frame members 41 and 42, which are preferably formed of telescoping sleeves or pipes 43 and 44. Suitable cross braces 45 connect the inner end portions of the sleeves 43 of the frame member 41 and the pivot rod 40 connects said frame member and sleeves to the eyes 39 of the carriage. Thus, the inner end portion of the frame member 41 overlies and rests upon the carriage. Suitable abutment plates 46 are secured to the outer end of the top 22 of the carriage for maintaining the frame member 41 in a horizontal plane when it is swung downwardly into engagement therewith.

The sleeves 44 of the outer frame member 42 telescope over the sleeves or pipes 43 of the inner frame member 41, whereby the effective length or projection of the stage 38 may be varied by moving said outer frame member relative to said inner frame member. A pair of longitudinal bars 47 are disposed between the sleeves 43 and have their inner end portions secured to the cross braces 45 of the inner frame member. As is most clearly shown in Fig. 3, a winch mechanism 48 is mounted on the outer end of the bars 47 between the sleeves of the outer frame member and includes a transverse shaft 49 upon which a suitable reel 50 is mounted. The latter is adapted to receive a cable 51 which has its free ends connected to opposite ends of the outer frame member as shown by the numerals 52 and 53. A reversible ratchet lever 54 is mounted on one end of the shaft 49 for rotating the same so as to cause the reel 50 to travel relative to the cable 51 and thereby reciprocate or slide the outer frame member relative to the inner frame member. Suitable cross braces 55 connect the ends and intermediate portions of the pipes or sleeves 44

of the outer frame member and a foraminous screen or deck plate 56 of expanded metal is mounted thereon. The lever 54 projects through a slot or opening 56' formed in the deck plate 56.

5 A guard is provided for the stage 38 by means of standards or posts 57 which are pivotally connected to the corners of the outer frame member and have pins 58 at their upper ends for removably receiving eye bars or rods 59. Due to the 10 pivotal mounting of the posts 57 and the removability of the rods 59, said posts may be folded downwardly when it is desired to swing the stage upwardly as shown in Fig. 1. To facilitate upward swinging of the stage, a portable hoist 60 is 15 suitably suspended from the upper end of the frame 14 and an eye 61 is secured to the outer cross bar 55 of the outer frame member 42 for receiving the hook 62 carried by the chain 63 of the hoist. A similar eye 64 is carried by the innermost cross bar 45 of the inner frame member, whereby the hoist may be utilized to raise and lower the stage and its carriage 21 relative to the guide channels 15.

In use, the derrick platform structure is lifted 25 into a derrick by means of the eye 69 at the upper end of the frame 14 and the legs 16 of said frame are secured to one of the sides of the derrick by means of the brackets 18 and the J-bolts 18' which engage the girders 11 of said derrick side.

30 In installing the platform structure, the stage 38 is swung upwardly by means of the hoist 60 so as to be disposed adjacent the channels 15. When it is desired to use the platform, the stage is swung downwardly so as to overlie the carriage 21 and extend horizontally toward the center of the derrick. By swinging the posts 57 upwardly and engaging the eye bars 59 upon the pins 58 of said posts, a workman may stand upon the stage without danger of falling therefrom. The hook 62 of the hoist chain 63 is disengaged from the eye 61 and engaged with the eye 64 for adjusting the vertical position of the stage. As has been explained, the carriage and stage may be moved upwardly relative to the channels 15 due 40 to the spring-pressed arrangement of the latch mechanism 28. However, when it is desired to lower the carriage and stage, it is necessary to depress the lever 32 so as to swing the pawls 31 outwardly away from the channels and their stops 27. The projection or length of the stage may be 45 readily varied by actuation of the ratchet lever 54 which causes rotation of the shaft 49 and its reel 50 whereby one end of the cable is taken up and the other end is payed out. Due to the telescoping arrangement of the sleeves 43 and 44, the frame member 42 is moved relative to the frame member 41 upon actuation of the lever 54. By reversing the lever, the outer frame member may be moved in the opposite direction relative to the inner frame member. As has been pointed out hereinbefore, the stage 38 may be swung upwardly out of the way whenever desired.

55 Due to the construction of the derrick platform, the same may be readily mounted within 65 a derrick or removed therefrom in a relatively short period of time. Although primarily adapted to be used in running or stabbing well casing, pipes and rods, the derrick platform structure may be employed advantageously in packing the swivel 70 which is connected to the upper end of the drill stem, fastening the cementing head or connection to the top or upper end of the casing which is not cut off until after cementing the casing as well as for other well operations. In running or stabbing casing, it is of utmost importance that

the derrick platform be readily adjustable because the casing varies in length. This is particularly true where used or second-hand casing is employed. By vertically adjusting the platform relative to its support, a workman may be positioned in close proximity to the upper end of this casing so as to eliminate or materially reduce the possibility of injury due to his becoming overbalanced.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A platform structure for use in derricks including, a support adapted to be fastened to one side inwardly of a derrick and having upright guide means, a carriage slidably mounted on the guide means so as to be movable vertically of the derrick, the carriage having a horizontal frame at its upper end projecting inwardly of the derrick from said guide means, a rectangular working platform having one end portion resting upon and supported by the horizontal frame of the carriage with its opposite end portion extending inwardly thereof, the platform having the extremity of said one end portion pivotally attached to said carriage frame adjacent said guide means whereby said platform is pivotal upwardly into parallel contiguous relation to said guide means.

2. A platform structure as set forth in claim 1 including, spaced stops on the guide means, a latch pivotally mounted on the carriage below its

frame, and a pedal pivotally supported by and projecting above the carriage frame and having connection with the latch for actuating the same.

3. A platform structure as set forth in claim 1 wherein the intermediate portion of the platform rests upon the inner margin of the carriage frame.

4. A platform structure as set forth in claim 1, the working platform including tubular members carrying a load supporting surface, and elongate complementary members telescoping said tubular members and having their extremities pivotally attached to the carriage frame adjacent the guide means.

5. A platform structure as set forth in claim 1, the guide means being a pair of spaced upright channel members, retaining rollers on the carriage engaging in said members, vertically spaced lugs on the members, and locking pawls on the carriage for engaging the lugs and supporting the carriage at selected elevations on the channel members.
